UNITED STATES PATENT OFFICE.

GUSTAV F. ANDERSON, OF BROOKLYN, NEW YORK.

CLOSURE FOR RECEPTACLES.

Application filed May 7, 1921. Serial No. 467,739.

To all whom it may concern:

Be it known that I, GUSTAV F. ANDERSON, a subject of the King of Sweden, and a resident of the borough of Brooklyn, in the county of Kings, city, and State of New York, have invented certain new and useful Closures for Receptacles, of which the following is a specification.

This invention relates to closures for receptacles, and it is the object of the invention to provide a closure so constructed and arranged whereby as the closure is applied to the opening of a receptacle the air between the contents of the receptacle and the closure will be expelled during the applying of the closure to the receptacle opening.

It is another object of the invention to provide a closure of this character comprising a disk to engage the rim of the receptacle opening and having a skirt to pass downwardly over the wall of the opening, said skirt having longitudinal corrugations circumferentially disposed around the same to maintain communication between the exterior and interior of the receptacle as the closure is applied thereto, and means being provided to enter the opening to displace and expel the air between the material in the receptacle and the closure as the latter is applied to the receptacle.

It is a further object of the invention to provide a receptacle closure of this character in which the skirt is arranged with a screw thread to co-operate with the thread about the opening of the receptacle, said skirt having longitudinal corrugations intersecting the skirt thread whereby the closure may be applied to the receptacle by a rotary movement thereof.

Other objects and inventions will hereinafter appear.

In the drawing and accompanying and forming a part of this specification Figure 1 is a side elevation, partly in section, of a closure showing an embodiment of my invention applied to the opening of a receptacle, such as the neck of a bottle.

Figure 2 is a sectional side elevation of the component parts of the closure showing the same in separated condition and in relation to the threaded neck of a bottle.

Figure 3 is a perspective view of the closure shown in Figure 1 looking at the top and side.

Figure 4 is a perspective view of a seal-

ing member to be interposed between the closure proper and the rim of a receptacle opening.

Figure 5 is an enlarged fragmentary sectional view in perspective of the closure means and receptacle to show the application of the closure thereto and the sealing of the closure; and

Figure 6 is a sectional side elevation of a modification of the closure showing the parts in disassembled relation.

Similar characters of reference designate like parts throughout the different views of the drawing.

The embodiment of my invention shown in the drawing comprises a disk member having a depressed portion 7 to engage within the opening of a receptacle, such as the mouth of a neck of a receptacle 8. The disk member has a skirt or body portion 9 to be passed downwardly over the neck of a receptacle as shown in Figures 1 and 2, and is formed with a bead 10 at the outer edge by rolling the material of the skirt outwardly. The skirt is provided with a rolled thread 11 to co-operate with the usual thread 12 formed on the outer surface of the receptacle to apply the closure to the receptacle by a rotary movement.

As stated it is an object of the invention to displace the air in the receptacle above the contents of the receptacle and the closure in applying the closure by the entering of the depressed portion 7 of the closure in its passage into the receptacle, and to permit of the escape of said air a series of passages are provided communicating with the interior and exterior of the receptacle. These passages are arranged by

corrugating the skirt of the closure, these corrugations extending longitudinally of the skirt and being circumferentially disposed around the skirt, as shown at 13, with the corrugations intersecting the thread 11 and extending from the end, or adjacent the beaded portion 10, of the skirt to beyond the juncture of the skirt with the disk portion of the closure, as clearly shown at 14, in Figures 1, 2 and 5. The depressed portion 10 of the disk and the corrugations of the skirt are so arranged that there is an annular flat portion interposed between the juncture of the corrugated skirt and the disk portion forming a seat to engage the rim of the wall of the receptacle opening, as clearly shown at 15.

It will be obvious that in applying the closure to the receptacle the closure is rotated to cause the closure thread to co-operate with the receptacle thread to draw the closure to the receptacle outlet, and as the closure is applied to the receptacle the depressed portion 7 will enter the opening in the receptacle, or the mouth of the neck of a receptacle. As the corrugations 13 intersect the threaded portion of the skirt of the closure there will be provided a series of unobstructed openings communicating with the interior and exterior of the receptacle permitting of the ready flow of the air from the receptacle displaced by the depressed portion of the closure entering the opening, and as the closure is drawn home to the rim of the receptacle opening the annular seat 15 will firmly engage such rim of the wall of the opening shutting off communication with the interior of the receptacle through the passages formed by the corrugations 13.

To prevent the contents of the receptacle from coming in contact with the inner surface of the closure with the possible corrosion of the material of the closure due to chemical action or otherwise and the consequent spoiling of the material in the receptacle, and to also serve as a means to seal the connection between the annular seat 15 and the rim of the receptacle opening, a disk of sealing material 16 is provided which may comprise a disk of paraffined paper. This sealing disk is preferably arranged with radial flutes or corrugations as clearly shown in Figures 2 and 4 whereby it is adapted to readily adjust itself to the contour of the inner face of the depressed portion of the disk and obviating the possibility of rupturing said sealing disk by undue strain thereon as the closure is applied to the receptacle. Furthermore, these flutes will facilitate the expelling of the air between the depressed portion of the closure and material in a receptacle as the closure is applied to the latter.

In the modification shown in Figure 6 the structure of the closure is substantially the same as that illustrated and described in connection with Figures 1 and 2, but instead of depressing the disk to provide the means to displace the air between the closure and surface of the material in a receptacle and making the same integral with the disk, such means consists of a separate member 17 which is constructed and arranged to be inserted into the closure. In this form of the closure means the member 17 constitutes the closure proper the same being arranged with an annular flange 18 to engage the rim of the receptacle opening and is firmly drawn thereto by the disk member the latter serving as a securing means for the member 17. The operation of applying the

closure shown in Figure 6 is substantially the same as that described in connection with Figures 1 to 5. The sealing disk 16 is also used in the arrangement of the closure shown in Figure 6 to serve as a sealing means and a protecting shield for the inner surface of the member 17.

Variations may be resorted to within the scope of my invention and portions thereof may be used without others.

Having thus described my invention I claim:

1. A receptacle and a closure therefor comprising a disk member to engage the rim of the receptacle opening, and a skirt portion to engage the receptacle and arranged with passages extending from the peripheral portion of the skirt to the juncture thereof with the disk to maintain communication between the interior and exterior of the receptacle as the closure is applied to the latter.

2. A receptacle and a closure therefor comprising a disk member to engage the wall of the receptacle opening and having a skirt to engage the receptacle arranged with corrugations to co-operate with the receptacle to form passages between the receptacle and closure to maintain communication between the exterior and interior of the receptacle during the application of the closure for the purpose specified.

3. A receptacle closure comprising a disk member having an integral skirt portion arranged with longitudinal corrugations circumferentially disposed around the skirt and extending from the end of the skirt to beyond the juncture of the skirt and disk member for the purpose specified.

4. A closure for receptacle openings comprising a disk portion arranged with a depressed portion to engage within the receptacle opening when applied to the receptacle, and having a skirt arranged with longitudinal corrugations to maintain communication between the exterior and interior of the receptacle as the closure is applied thereto for the purpose specified.

5. A closure for receptacle openings comprising a disk portion arranged with a depressed portion to engage within the receptacle opening when applied to the receptacle, a skirt integral with the disk portion, longitudinal corrugations circumferentially disposed around the skirt extending from the end to beyond the juncture of the skirt with the disk portion, and an annular seat arranged between the depressed portion of the disk and the corrugations of the skirt to engage the rim of the receptacle opening for the purpose specified.

6. A closure for receptacle openings comprising a disk portion having an integral skirt arranged with longitudinal corrugations circumferentially disposed around the

same to provide passages communicating with the exterior and interior of the receptacle as the closure is applied thereto, and a sealing and lining material interposed between the disk portion and the rim of the receptacle opening.

7. A closure for receptacle openings comprising a disk portion to close and engage over the rim of the opening and a threaded skirt portion to pass downwardly over the neck of a receptacle and co-operate with a thread upon the receptacle to secure the closure thereto, and said skirt having longitudinal corrugations intersecting the threaded portion thereof to maintain communication between the exterior and interior of the receptacle as the closure is applied thereto for the purpose specified.

8. The combination with a receptacle having a neck arranged with an exterior screw thread, of a closure for the opening in the neck comprising a disk portion with an integral threaded skirt to be passed downwardly over the neck of the receptacle by the co-operation of the threads of the closure and receptacle as rotary movement is imparted to the closure; longitudinal corrugations circumferentially disposed around the skirt and extending from the end to beyond the juncture of the skirt with the disk portion to maintain communication between the exterior and interior of the receptacle as the closure is applied thereto; and a depressed portion to enter the mouth of the neck as the closure is applied thereto for the purpose specified.

9. The combination with a receptacle having a neck arranged with an exterior screw thread, of a closure for the opening in the neck comprising a disk having a depressed portion to enter the mouth of the neck as the closure is applied thereto and an integral screw threaded skirt to co-operate with the neck threads to apply the closure to the receptacle by a rotary movement, said skirt having longitudinal corrugations circumferentially disposed around the same extending

from the end to beyond the juncture of the skirt with the disk portion, and an annular seat arranged between the depressed portion 50 of the disk and the ends of the corrugations for the engagement of the rim of the neck for the purpose specified.

10. The combination with a receptacle having a neck, of a closure for the opening 55 in the neck comprising a disk having a depressed portion of substantially the same diameter as the mouth of the neck to enter the mouth of the neck and a skirt integral with the disk to pass downwardly over the 60 receptacle neck having longitudinal corrugations circumferentially disposed around the same, and extending from the end to beyond the juncture of the skirt with the disk, and a disk of sealing material to cover the 65 interior of the closure disk and the peripheral portions interposed between the closure and rim of the receptacle, said sealing disk being arranged for circumferential enlargement when the closure is applied to the 70 receptacle for the purpose specified.

11. The combination with a receptacle having a neck arranged with an exterior screw thread, of a closure for the opening in the neck comprising a disk having a depressed portion to enter the mouth of the neck, a skirt integral with the disk arranged with a screw thread and longitudinal corrugations circumferentially disposed around and intersecting the screw thread of the skirt 75 to apply the closure by a rotary movement and maintain communication between the exterior and interior of the receptacle as the closure is applied thereto; and a radially fluted disk of sealing material to cover the 80 surface of the depressed portion of the disk exposed to the interior of the receptacle with the peripheral portions adapted to extend and engage between the disk and rim of the receptacle neck when the closure is applied 85 thereto.

Signed this 22nd day of April, 1921.

GUSTAV F. ANDERSON.
